UNITED STATES PATENT OFFICE.

OTTO POTT, OF QUINCY, ILLINOIS.

ADJUSTABLE SCAFFOLD.

Application filed May 24, 1928. Serial No. 280,355.

This invention relates to adjustable scaffolds, and has more particular reference to an improved portable knock-down scaffold which is adjustable in height.

5 The primary object of the present invention is to provide a scaffold of the above kind having a traveling platform seat which may be readily shifted horizontally by the workman occupying the same, thereby 10 greatly facilitating the execution of interior or exterior decorative and other work.

A further object is to provide an adjustable or extensible scaffold which is simple and durable in construction, light in weight, 15 and adapted to be readily erected for use or knocked down into compact form for storage or transportation.

A still further object is to provide a four-pillar adjustable scaffold, in which the 20 pillars are effectively connected and braced against swaying when the scaffold is set up for use.

The invention consists of the novel form, combination and arrangement of parts hereinafter more fully described, shown in the accompanying drawings and claimed.

In the drawings:—

Figure 1 is a side elevational view of a scaffold embodying the present invention.

30 Figure 2 is a top plan view thereof.

Figure 3 is an end elevational view of the same.

Figure 4 is an enlarged fragmentary detail view of one of the pillars and adjacent parts, partly in elevation and partly in vertical section.

Figure 5 is an enlarged horizontal section through one of the pillars, taken on line 5—5 of Figure 1;

40 Figure 6 is an enlarged fragmentary section on line 6—6 of Figure 2.

Fig. 7 is a detailed sectional view.

Referring more in detail to the drawings, the present scaffold embodies four similar extensible corner posts or pillars, each including a hollow lower section 5 provided with a supporting base, preferably in the form of crossed bars 6 having caster wheels 7 at the ends thereof, and a hollow 50 upper section 8 slidably telescoped in the

lower section 5. These pillar sections are preferably formed of boards bound at the top and bottom by bands or hoops 9 and of rectangular form in cross section to prevent relative turning of the pillar sections. 55 Journaled on a horizontal spindle 10 in the upper end of each lower pillar section 5 is a pulley 11, and passing over this pulley is a rope 12 which has one end attached to the lower end of the associated upper pillar section 8 as at 13, and which has its other end attached to the drum of a small windlass which is journaled as at 14 in the lower end of the lower pillar section. The upper pillar section has longitudinal elongated slots 15 in opposite sides thereof through which the spindle 10 projects for permitting the upper pillar section to be raised or lowered, and in order to promote the ease of movement of said upper pillar section, pairs of antifriction rollers 16 are journaled on opposite sides of the lower end thereof to ride on the inner surfaces of the adjacent walls of the lower pillar section. 60 65 70 75

The pillars are separably connected at the ends and sides of the scaffold and held in operative relation to each other by means of pairs of folding connecting bars 17 separably connected in any suitable manner at 80 18 and having releasable braces 19. To prevent spreading of the upper pillar sections at each end of the scaffold, the upper ends of said sections are connected by detachable connecting chains 20. 85

In view of the above, it will be apparent that the erected scaffold may be readily moved on the floor to the desired place, after which the windlasses 14 may be operated to raise or lower the upper platform-supporting sections 8 of the pillars to suit the height of the work to be done. To hold the upper sections of the pillars in their various vertically adjusted positions, each is provided with a longitudinal series of holes 21 for selective reception of a removable pin 22 whose ends are adapted to project and rest on the upper end of the associated lower pillar section, thus relieving the ropes 12 of 100 90 95

the weight imposed on the platform of the scaffold.

The upper ends of the upper pillar sections at each side of the scaffold are connected by a detachable track rail composed of a pair of spaced parallel bars 23 rigidly connected together as at 24. The upper ends of the pillar sections 8 are bifurcated to receive the track rails, and the legs of the bifurcations are connected by cross pins 25 adapted to seat in undercut notches 26 provided in the lower edges of the bars 23 forming said rails. Due to the undercut form of the notches 26, the rails are locked to the pillars until the latter are disconnected at 18 and moved slightly together, thus preventing accidental detachment of the rails when the scaffold is properly set up for use.

A platform seat 27 is provided for movement on the track rails from end to end of the scaffold, the seat having rollers 28 adapted to ride on the bars 23 of the rails and formed with central flanges 29 to fit between said bars and prevent lateral displacement 25 of the seat off of the track rails.

Ropes 30 pass around pulleys 31 on the opposite ends of the track rails and have their ends attached to opposite sides of the workman's seat or carriage as at 32. It is thus apparent that the workman, while occupying the seat, may readily shift the seat or carriage horizontally and correspondingly vary his position as the work progresses, by pulling on the intermediate portions of 35 the ropes 30 in the desired direction.

By separating the bars 17 at 18, the pillars may be shifted to permit detachment of the track rails. The bars 17 may then be folded and the pillars collapsed so that 40 the scaffold may be knocked down in compact form for convenient storage or transportation from one place to another.

Minor changes may be made without departing from the spirit and scope of the invention as claimed.

What I claim as new is:

1. A scaffold of the character described comprising upright corner pillars, horizontal track rails mounted on top of said pillars, a workman's seat carriage movably mounted on said rails, means operable by the workman while occupying said seat carriage for moving the latter on said track rails, said last-named means embodying pulleys 50 mounted on the opposite ends of one of said track rails, and a flexible member passing around said pulleys and having its ends attached to opposite sides of said seat carriage.

2. A scaffold of the character described comprising upright corner pillars, horizontal track rails mounted on top of said pillars, a workman's seat carriage movably mounted on said rails, said pillars having 65 cross pins at the upper ends thereof, said

track rails having undercut notches in their lower edges to receive said cross pins.

3. A scaffold of the character described comprising upright corner pillars, horizontal track rails mounted on top of said pillars, a workman's seat carriage movably mounted on said rails, said pillars having cross pins at the upper ends thereof, said track rails having undercut notches in their lower edges to receive said cross pins, and 70 pairs of separably connected folding bars carried by said pillars for connecting the latter in set up relation.

4. A scaffold of the character described comprising upright corner pillars, horizontal track rails mounted on top of said pillars, a workman's seat carriage movably mounted on said rails, said pillars having cross pins at the upper ends thereof, said track rails having undercut notches in their lower edges to receive said cross pins, pairs 80 of separably connected folding bars carried by said pillars for connecting the latter in set up relation, said pillars embodying telescopically associated upper and lower sections, and means to vertically adjust said upper pillar sections for varying the elevation of said track rails, said folding bars being carried by said lower pillar sections.

5. A scaffold of the character described comprising upright corner pillars, horizontal track rails mounted on top of said pillars, a workman's seat carriage movably mounted on said rails, said pillars having cross pins at the upper ends thereof, said track rails having undercut notches in their lower edges to receive said cross pins, pairs 90 of separably connected folding bars carried by said pillars for connecting the latter in set up relation, said pillars embodying telescopically associated upper and lower sections, means to vertically adjust said upper sections, said folding bars being carried by said lower pillar sections, said adjusting means embodying windlass drums mounted 100 in the lower ends of the lower pillar sections, pulleys mounted in the upper ends of said lower sections, and ropes attached to the lower ends of the upper sections and to the drums and passing over said pulleys.

In testimony whereof I affix my signature.

OTTO POTT.
